SHOE JACK

Joseph Amico, Rochester, N. Y., assignor, by
mesne assignments, to Charles Norbert Bag-
lin

Application May 11, 1937, Serial No. 141,896

9 Claims. (Cl. 12—123)

The object of this invention is to provide a combination shoe jack and last that can be used on a great variety and sizes of shoes, more especially for supporting the shoe during repair work.

Another object of the invention is to provide a device that will separately support the forward part of the sole of the shoe and the heel of the shoe and stretch the shoe between them.

10 Another object of the invention is to provide a swiveled heel support having a separate support on each end thereof, each of which supports can be brought to operative position with reference to the last by rotating the support on its axis.

15 Another object of the invention is to swivel the last and shoe support on a vertical axis, so that it can be turned to a variety of positions, bringing each time a different part of the shoe before the operator.

20 Another object of the invention is to make the device adjustable in height, so as to place the repair work before the mechanic to the best advantage.

25 These and other objects of the invention will be illustrated in the drawings, described in the specification, and pointed out in the claims at the end thereof.

In the drawings:

Figure 1 is a side elevation of the jack and shoe support.

Figure 2 is a vertical section through the base of the support.

Figure 3 is a vertical section through the base of the support, the section being taken on a line 35 at right angles to the section shown in Figure 2.

Figure 4 is a horizontal section through the base of the support, the section being taken on the line 4x—4x of Figure 3.

Figure 5 is a longitudinal vertical section 40 through the upper part of Figure 1.

Figure 6 is a vertical section through the upper part of Figure 1, the section being taken on the line 6x—6x of Figure 5, looking in the direction of the arrow.

45 Figure 7 is a vertical section through the last holder, the section being taken on the line 7x—7x of Figure 5, the last being omitted.

Figure 8 is an end elevation of the arm and heel sets.

50 Figure 9 is a side elevation of a last for a man's shoe.

Figure 10 is a sectional view through the intermediate part of the upright shown in Figure 1, 55 showing the vertical adjustment therein.

Figure 11 is a cross section through the last on the line 11x—11x of Figure 9.

In the drawings like reference numerals indicate like parts.

5 In the drawings reference numeral 1 indicates a base having an upright annular flange 2 thereon, forming a pocket in the center thereof. In this pocket rests a sleeve 3 having an annular flange 4 extending out therefrom at an intermediate point thereon. Surrounding the upper part 10 of this sleeve is a tubular support 5 extending upwardly therefrom. In the upper part of this tubular support is a sleeve 6 having an annular collar 7 thereon, which collar rests on the upper end of the tube 5. On the upper end of the 15 sleeve 6 is a tube 8 extending upwardly therefrom, the lower end of which rests on the collar 7.

The annular flange 2, the sleeve 3, the tube 5, the sleeve 6, and the tube 8 all form an upright column. The tubes 5 and 8 and the sleeve 6 are 20 clamped together by the set screws 9 and 10, so that the three parts form an integral column which can be turned on its vertical axis.

25 In the sleeve 6 are provided extra threaded holes 11 and 12 for the purpose of giving vertical adjustment to the sleeves 5 and 8. The bolts 9 or 10, or both of them, can be withdrawn from the holes in the sleeve 6 with which they are shown engaged, and can then be engaged with the holes 11 and 12, or both of them. This will 30 have the effect of raising the tube 8 by several inches, bringing it to a more convenient position for the operator that is working with a shoe mounted on this device.

35 The sleeve 3 has an annular groove 13 therein, in which engages a screw 14 which holds it positively in the pocket formed by the annular flange 2, but permits it to turn freely therein. In the sleeve 3 is a series of vertical slots 15 shown in Figures 2, 3 and 4, in which engages 40 the dog 16 pivoted on a bracket 17 formed on the base 1. The upper edge of the dog 16 is concentric with the pivot 17a and works through a slot 18 in the flange 2 and engages in any one of the vertical slots 15. Six of these slots 15 are 45 shown, permitting the upright column to turn to any one of six different positions, equally spaced apart, and permitting the work to be placed in six different positions with reference to the operator.

50 On top of the tube 8 is supported a head 20, which has a sleeve 21 formed on the bottom thereof that engages in the tube 8 and to which it is rigidly fastened by the screw 22. On one end of this head is a web 22a on which is formed a boss 55

23. On this boss swings an arm 24, on each end of which is a heel set 25 and 26. The heel set 25 is intended to fit a lady's shoe and the heel set 26 is intended to fit a man's shoe. In the intermediate part of the arm 24 is a hub 27 having lugs 28 projecting forwardly therefrom, which engage in suitable recesses in the web 22a.

5 Through the boss extends a bolt 29 provided with a thumb nut 30 on the outer end thereof 10 with a washer 31 which rests against the hub 27 of the arm 24. A spring 32 surrounds this bolt. By turning the thumb nut 30, the bolt is drawn to the left in Figure 5, compressing the spring. This draws the arm 24 firmly against the web 15 22a, locking the lugs 28 in the recesses and holding the arm 24 firmly against rotation, so that the one heel set or the other is held in the uppermost position and in line with the last 33.

20 The head 20 is channel-shaped and in the channel slides the last support 34, in the upper end of which is provided a socket in which engages the upright on the last 33. Lasts of different shape are interchangeable in this socket.

25 An opening 35 extends through the bottom of the last support, and in this opening is provided a tension spring 36, one end of which is fastened to the head at 37 and the other end of which is fastened to the last support at 38. This spring normally holds the last support and the last to 30 the right, but permits it to be pushed to the left. The toe of a shoe can be placed on the last, and the shoe and the last can be pushed to the left until the inside of the shoe engages over the heel set 25, after which the operator lets go and the spring 36 contracts and moves the last 33 to the 35 right, stretching the shoe between the last and the heel set. The last support can be made stationary by tightening up on the set screw 40. With the shoe in position, the operator can press 40 on the treadle 41, release the dog from the upright column, and turn the column to bring the shoe to any position that is desired, after which the dog engages one of the slots 15 and locks the shoe in the desired position for work thereon.

45 I claim:

1. In a shoe jack, the combination of a base and upright, a head on the top thereof, a heel set on one end of said head and projecting above it, a last slidably mounted on the other end of said head and projecting above it, said last and said heel set being capable of being inserted in a shoe and being capable of supporting the shoe between them.

50 2. In a shoe jack, the combination of a head, a heel set on one end of said head and projecting above it, a last on the other end of said head and projecting above it, said last and said heel set being capable of being inserted in a shoe and being capable of supporting a shoe between them, said head being mounted to turn on its vertical axis so as to present different parts of the shoe to the operator.

55 3. In a shoe jack, the combination of a head, a web on the end of the head, an arm mounted to swing on a horizontal axis on the end of said

head and extending up and down from said axis, a heel set on each end of said arm, said arm being capable of being turned on its horizontal axis so as to bring either heel set to the uppermost position, a last capable of engaging in the toe of a shoe placed on the head opposite the heel set and in line therewith when the heel set is in its uppermost position, said last being capable of moving to and from the heel set.

60 4. In a shoe jack, the combination of a head, a web on the end of the head, an arm mounted to swing on a horizontal axis on the end of said head and extending up and down from said axis, a heel set on each end of said arm, said arm being capable of being turned on its horizontal axis so as to bring either heel set to the uppermost position, means for locking the arm with either heel set in its uppermost position, a last capable of engaging in the toe of a shoe placed on the head opposite the heel set and in line therewith when the heel set is in its uppermost position, said last being capable of moving to and from the heel set.

65 5. In a shoe jack, the combination of a head, a channel in said head, a last support adapted to slide horizontally in said channel, a last mounted in said last support, a heel set mounted on one end of said head, said last and said heel set being adapted to support a shoe between them.

6. In a shoe jack, the combination of a head, a channel in said head, a last support adapted to slide horizontally in said channel, a last mounted in said last support, a spring attached to said last support and attached to one end of the arm, a heel set at the other end of the arm, said spring being adapted to draw the last away from the heel set.

7. In a shoe jack, the combination of a head, a web on the end of the head, an arm mounted to swing on a horizontal axis on the end of said head and extending up and down from said axis, a heel set on each end of said arm, said arm being capable of being turned on its horizontal axis so as to bring either heel set to the uppermost position, a last capable of engaging in the toe of a shoe placed on the head opposite the heel set and in line therewith when the heel set is in its uppermost position.

8. In a shoe jack, the combination of a head, a last on the head, an arm pivotally mounted on one end of the head and having two heel sets thereon, said arm being capable of rotation to bring either heel set up into line with the last.

9. In a shoe jack, the combination of a base and an upright, a head on top thereof, a plurality of heel sets on one end of said head, said heel sets being rotatably mounted so as to project above the head one at a time, a last slidably mounted on the other end of said head and projecting above it, said last and one of said heel sets being capable of being inserted in a shoe and being capable of supporting the shoe between them.
